UNITED STATES PATENT OFFICE.

JOSE STERN, OF CHICAGO, ILLINOIS.

DESIGN FOR A MEDAL.

SPECIFICATION forming part of Design No. 21,255, dated December 22, 1891.

Application filed August 13, 1891. Serial No. 402,564. Term of patent 3½ years.

To all whom it may concern:

Be it known that I, JOSE STERN, a citizen of the United States, residing at Chicago, county of Cook, State of Illinois, have invented a certain new and useful Improvement in a Design for a Medal; and I declare the following to be a full, clear, and exact description of the same, such as will enable others skilled in the art to which it pertains to make and use the same, reference being had to the accompanying drawings, which form a part of this specification.

In the drawings, Figure 1 is a view of the obverse side of my medal, and Fig. 2 a view of the reverse side thereof.

The leading feature of my design is the head of Christopher Columbus A, centrally set upon the obverse side of the medal. This head is surrounded by a circle composed of the words "Christoforo Colombo" B, the dates 1492-1893 C, and the laurel branches D; but these words and dates can of course be changed or altered, they forming no part of my invention. The head represents a profile view of the subject, with a head-covering a and long hair a'. A beard a² extends from the ears around to the chin, and a mustache a³ adorns the upper lip. Outside of the circle

of words and dates is another circle E, made up of minute straight lines extending radially from a circular line. Upon the reverse side of the medal is the design of a tower F in the foreground, with a series of buildings G and a marine scene, with steam and sailing vessels in the background. Under the tower are the words "Proctor Tower." Around the above-described scene is a circle formed of the words "Columbian Exposition, Chicago, Ill., United States of America," and outside of this is a circle made up of radial lines similar to that on the obverse side; but the above words may of course be altered or omitted.

What I claim is—

The design for a medal, as described and shown, consisting of a conventionalized head of Christopher Columbus in profile on the obverse side of the medal, while on the reverse side is a tower in the foreground, with a marine scene in the background, substantially as described.

In testimony whereof I sign this specification in the presence of two witnesses.

JOSE STERN.
